In Germany February 12, 1938

6 Claims. (Cl. 221—78)

This invention relates to containers for substances of pasty consistency (hereinafter referred to as paste) having means for dispensing the contents in variable portions as and when required, without the necessity for removing the container lid or closure.

Objects of the invention are firstly to provide a simple, handy and effective paste dispensing device of this character capable of being manufactured easily and cheaply, and secondly, to ensure at all times a hygienic discharge or extrusion of the contents of the device.

A paste dispensing device in accordance with the invention comprises an internally round, closed container having a paste discharge opening in one of its walls, a post fixed centrally in the container, two radial vanes extending one rotatably and the other non-rotatably from the post to the inner peripheral wall of the container and means for rotating the rotatable vane from the exterior of the container. The device may also include means for automatically sealing and unsealing the discharge opening on opposite directional movements of the rotatable vane.

Preferably one end wall of the container is constituted by a rotatable lid having the paste discharge opening therein and also having, near said discharge opening, an inwardly projecting pin or equivalent to engage and rotate the rotatable vane.

The rotatable vane has or may have a bent-over portion adapted to cover and uncover the paste discharge opening on initial movements of the lid in opposite directions, the pin or equivalent engaging a slot in the bent-over portion to permit limited relative rotation of the lid and vane.

One embodiment of the dispensing means as applied to a conventional form of metal box suitable, for example, for containing face cream or toilet cream, and to be carried in a lady's handbag, is illustrated on the accompanying drawing to which reference will now be made.

Fig. 1 is an exploded perspective view of the complete device.

Fig. 2 is an inverted plan view partly with the base broken away.

On the drawing 1 denotes the body of the box or container, and 7 the lid or closure. Internally, the depending flange of the box lid 7 has spaced circumferential grooves 10 to interlock with spaced external projections 9 on the reduced neck of the box body 1. Thereby the lid can be fitted to the box body in one position but is retained against removal during its sub-

sequent rotation for the purpose hereinafter explained.

Inside the box body 1 is fixed as by soldering a central post 2 adapted to receive the bosses 3a and 4a of two radial vanes 3 and 4 respectively. 5 This post 2 has a key-way 2a extending for a part of its length and adapted to receive a key or feather fixed in the boss 4a of the vane 5, whereby this vane is held immovable. The other vane 3 is free to rotate about the axis of the post. 10

The box lid 7 has a paste discharge opening 8, and it also has an inwardly projecting pin 6 which is adapted to engage a slot 3c in the bent-over portion 3b of the vane 3. The pin 6 may be 15 soldered in position on the lid.

With this construction only the parts 2 and 6 have to be integral with the box body 1 and lid 7 respectively, the vanes 3 and 4 being separately removable. This facilitates and also cheapens the cost of manufacture of the device as a whole. 20

It will be readily understood that after the vanes 3 and 4 have been mounted on the post 2 and after the vane 3 has been turned back to abut the vane 4, the box 1 may be charged with paste whereupon the lid 7 can be applied so that 25 the pin 6 engages the slot 3c. Under these conditions the relative positions of the parts will be as shown in the inverted plan view, Fig. 2. If now the lid 7 is turned in the direction of the arrow in Fig. 2, it will first of all be displaced 30 relative to the movable vane 3 to the extent permitted by the slot 3c. During this initial movement, the paste discharge opening 8 in the lid is uncovered and brought to a position in advance of the front surface of the movable vane 35 3 so that, on further movement of the lid in the direction of the arrow and consequent movement of the vane 3, paste is forced out of the discharge opening. A slight turning movement of the lid in the opposite direction immediately brings the 40 discharge opening 8 to a position in which it is sealed or covered by the bent-over portion 3b of the vane 3 so that the extruded paste is cleanly cut-off from the paste remaining in the box. Manifestly, the amount of paste discharged at 45 any one operation depends on the extent of forward turning movement imparted to the lid.

In those cases where only a small quantity is to be discharged at any one time, hardly any suction arises behind the rotatable vane 3 and the 50 provision of an air inlet opening is unnecessary, but if desired, a small air hole may be provided to counteract any suction effect that arises.

After substantially one complete turn of the lid, the leading edge of the vane 3 is brought 55

into contact with the vane 4 and the contents of the box have thereby been completely discharged. Upon turning the lid and the movable vane back to the original or starting position, the lid can be removed in order to charge the box with a fresh supply. Moreover, the vanes 3 and 4 can also be removed if required, as for the purpose of cleaning them and the interior of the box.

10 I claim:

1. A paste dispensing device comprising an internally round, closed container having a paste discharge opening in one of its walls, a post fixed centrally in the container, two radial vanes extending one rotatably and the other non-rotatably from the post to the inner peripheral wall of the container, means for rotating the rotatable vane from the exterior of the container, and means for sealing and unsealing the discharge opening on opposite directional movements of the rotatable vane.
- 15 2. A paste dispensing device comprising an internally round container, a rotatable lid for the container having a paste discharge opening therein, a post fixed centrally in the container, two radial vanes extending one rotatably and the other non-rotatably from the post to the inner peripheral wall of the container, and means projecting inwardly from the lid for rotating the rotatable vane on rotation of the lid.
- 20 3. A paste dispensing device comprising an internally round container, a rotatable lid for the container having a paste discharge opening

therein, a post fixed centrally in the container, two radial vanes extending one rotatably and the other non-rotatably from the post to the inner peripheral wall of the container, means projecting inwardly from the lid for rotating the rotatable vane on rotation of the lid, and means for sealing and unsealing the discharge opening on opposite directional movements of the rotatable vane.

4. A paste dispensing device according to claim 10 2, the rotatable vane having a bent-over portion adapted to cover and uncover the paste discharge opening on initial turning movements of the lid in opposite directions.

5. A paste dispensing device according to claim 15 3, the rotatable vane having a bent-over portion adapted to cover and uncover the paste discharge opening on initial turning movements of the lid in opposite directions.

6. A paste dispensing device comprising an 20 internally round container, a rotatable lid for the container having a paste discharge opening therein, a post fixed centrally in the container, two radial vanes extending one rotatably and the other non-rotatably from the post to the inner 25 peripheral wall of the container, the rotatable vane having a slotted, bent-over portion for sealing and unsealing the discharge opening on initial turning movements of the lid in opposite directions, and a pin on the lid engaging the slot in 30 said bent-over portion for rotating the rotatable vane on continued turning movement of the lid.

KARL PRINGSAUF.
